Primary Examiner — Darlington Ly(74) *Attorney, Agent, or Firm* — Barnes & Thornburg LLP(57) **CLAIM**

We claim the ornamental design for a folding tricycle, as shown and described.

DESCRIPTION

FIG. 1 is a front perspective view of the folding stroller tricycle according to the new design.

FIG. 2 is a front elevation view of the folding tricycle shown in FIG. 1.

FIG. 3 is a rear elevation view of the folding tricycle shown in FIG. 1.

FIG. 4 is a right side elevation view of the folding tricycle shown in FIG. 1.

FIG. 5 is a left side elevation view of the folding tricycle shown in FIG. 1.

FIG. 6 is a top plan view of the folding tricycle shown in FIG. 1; and,

FIG. 7 is a bottom plan view of the folding tricycle shown in FIG. 1.

The broken lines in the drawings illustrate portions of the folding tricycle that form no part of the claimed design.

1 Claim, 7 Drawing Sheets(56)
